CONNECTING MECHANISM

Robert Leicester Hall, Garden City, N. Y.

Application September 24, 1937, Serial No. 165,464

13 Claims. (Cl. 244—1)

This invention relates to a spring assembly mechanism and more particularly one adapted to present varying degrees of tension.

In many instances there is need for releasably holding two parts in close proximity and providing a tension to aid in maintaining them in such position. These objects have been generally accomplished by vacuum or pressure and have required some independent action in addition to the force pulling the bodies apart to release the pressure or vacuum.

The device of the present invention is adapted to present a high tensile force which offers a strong initial resistance to movement of the parts joined by the device, but which when once overcome may remain dormant permitting movement of the parts within limits and which as the parts are moved may provide a force to aid in maintaining them in their new position.

Another feature of the device of the invention is that it may be constructed to provide a resilient joinder member which presents a relatively high resistance to separation of the parts joined by it, which resistance when overcome by sufficient external force to separate the parts remains substantially inactive until the parts are brought approximately together again.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a longitudinal sectional view of one form of the invention in contracted position;

Fig. 2 is a cross-sectional view of the device as shown in Fig. 1, taken at right angles to the view shown in Fig. 1;

Fig. 3 is a longitudinal sectional view of the form of the invention shown in Fig. 1 in substantially extended position;

Fig. 4 is a vertical cross-section taken along the line 4—4 of Fig. 1;

Fig. 5 is a longitudinal cross-sectional view of another form of the device in contracted position;

Fig. 6 is a cross section of the form of device shown in Fig. 5 in extended position; and

Fig. 7 is a view of the device as applied in an airplane wing.

Referring now to the drawings, and particularly Figs. 1, 2 and 3; 1 represents a connecting

frame member which may be constructed as a cylinder. Cap members 2 and 3 may be placed at opposite ends of the cylindrical frame member and have openings 4 and 5 respectively therein, which in the case of a cylinder are preferably concentric therewith. These caps may be fastened to the frame member by any desirable means such as the rivets 6, 6 and 7, 7.

An extension rod 8 is fastened to one of the caps, here shown as cap 2, and secured thereto 10 by any suitable means such as the rivets 11, 11.

The extension rod 8 may have an eye 10 located adjacent one end for expediting attachment to a desired point.

A cylinder 9, smaller than the cylinder 1 is 15 adapted to slide through the opening in one of the caps such as 3. This cylinder is telescopically mounted within cylinder 1 and extends substantially the entire length of cylinder 1 and protrudes therethrough and may have attached 20 thereto as by the rivets 14, or other desirable means, an extension 12 which may have an eye 13 therein to facilitate attachment of the extension arm 12 to a desired point.

A spring 25 is located within the cylinder 9 25 and extension rod 8 and may be fastened at one end to the extension arm 8 by means of the spring retainer plate 26 having a spring attaching eye 28 therein. Spring plate 26 is in turn fastened to the extension rod 8 as by the bolt 27. The other 30 end of the spring 25 is fastened to the cylinder 9 as by the bolt 24 which may also serve to secure a cam plate 22 to the cylinder 9.

Control arms 18 and 19 are located within the cylinder or frame 1 and act through the trolley 35 wheels 16 and 17 which in one position ride in a depression or annulus 15 in the cylinder 1 to releasably and resiliently unite the cylinder 1 to the cylinder 9. These trolley wheels 16 and 17 are rotatably connected to the control arms 18 40 and 19 respectively by their respective axles 32 and 33.

One end of the control arms 18 and 19 is supported by trolley wheels 20 and 21 rotatably connected to the control arms by their respective 45 axles 34 and 35. The other ends of the control arms may be pivotally secured to a spring abutment collar 36 as at 30 and 31 respectively.

The spring abutment collar is adapted to slide between the cylinder 9 and cylinder 12 and serves 50 as a seat for one end of a spring 37 which is preferably substantially stronger than the spring 25 and is retained at its other end by a spring abutment collar 38 which is fastened to the cylinder 9 adjacent one end.

- In Figs. 1 and 2 the device is shown in its contracted position. In this position the ends 8 and 12 are being pulled together by the contractile force of the tensor spring 25 and the expanding force of the compression spring 37, their movement being limited by the abutment of cap 2 of the tube 1 against a resilient washer 38, interposed between the spring abutment collar 38 of the tube 9.
- 10 The parts are assembled in such fashion that in the contracted position of the mechanism the spring 25 is under tension and the spring 37 is under compression. Thus by the direct pull of the spring 25 the end members are held together
- 15 with the cylinders 1 and 9 telescoped.
- In addition to the direct effort of spring 25 an indirect closing force is exerted by the spring 37. This spring, under compression, is seated in the collar 38 which is fastened to the tube 9.
- 20 Its opposite end which abuts against the piston collar 36 tends to drive it forward. This force is in turn transmitted to the control arms 18 and 19, the end wheels 20 and 21 of which ride on the cam 22 in the contracted position thus forcing the trolley follower wheels 16 and 17 outwardly
- 25 into the groove formed by the annulus 15. Thus the expanding force of the spring 37 is transmitted to the outer tube 1 tending to contract the parts still further.
- 30 When sufficient separating effort is applied to the ends 8 and 12 to overcome the effort exerted by springs 25 and 37, the tubes 1 and 9 will slide relatively and the collar 38 and cap 2 separate. As the tubes 1 and 9 are moved toward their
- 35 extended positions the trolley wheels 16 and 17 will be held in the annulus 15 until the trolley wheels 20 and 21 ride down off the cam 22 onto the cylinder 9 to the position shown in Fig. 3. At this point the trolley wheels 16 and 17 will
- 40 disengage the annular groove 15 and the tube 1 will move without any resistance being offered by the spring 37 other than the frictional force transmitted by the trolley wheels 16 and 17 rolling on the inner face of the tube 1. In the form
- 45 of the invention shown in Figs. 1, 2 and 3 the limit of separation of the end parts 8 and 12 is governed by the length of the tube 1 from the annular groove 15 to the cap 2 and the extent to which the spring 25 is adapted to stretch.
- 50 It can thus be seen that once sufficient force has been exerted to bring the parts into the position where the trolley wheels 16 and 17 disengage the annular groove 15, the only force necessary thereafter to separate the parts to their
- 55 limit is one sufficient to overcome the tensile strength of the spring 25 which may be relatively weak. Yet, in this form of the device when the parts have been separated, they can be easily returned to their substantially contracted position
- 60 where both springs will again act to hold them in closed telescoped position.

In Figs. 5 and 6 I have shown a modified form of the invention, having not only means for presenting an initial high resistant force to separation but which when expanded gives a force substantially equal to its contractile force in the opposite direction. This form of the device may also be so designed as to present an initial resistance to compression which when overcome remains dormant during movement of the parts within limits.

In this form of the device there is a frame or cylinder member 51 having caps 52 and 53 on the ends thereof. These caps have holes 54 and 55 respectively in their ends substantially

concentric with the cylinder or frame 51 and are secured to the frame 51 by such means as the rivets 56 and 57. An extension rod 58 may be secured to the cap 52 by suitable means such as the bolt 61 passing through the end of the rod 58 and the cap 52. Adjacent the end of the rod 58 most removed from the cap 52, there may be a hole 63 adapted to aid in attaching the spring assembly mechanism to one of the points to which it is to be affixed.

10 Telescopically mounted within the cylinder 51 and the cap 52 and extending both beyond and substantially well up into the cylinder 51 in contracted position is a cylinder 59 having an extension arm 62 at one end thereof secured thereto by rivets 64 or other desirable means. Located in the end of the arm 62 most removed from the cylinder 59 may be a hole 63 to aid in attaching this end of the spring assembly mechanism to one of the parts to which the spring device is to be affixed. Intermediate the ends of the cylinder 51 at desired points are located two depressed annuli 65 and 73 which provide stops for trolley wheels 66 and 67, and 83 and 94, respectively, which travel between the outer cylinder 51 and the inner cylinder 59, and in engagement with the outer cylinder 51. These trolley wheels are mounted respectively on control arms 68, 69, 84 and 85. Control arms 68 and 69 are pivotally attached as at 75 and 79 to a spring abutment collar 86 which is slidable with respect to the cylinders 51 and 59. The control arms 84 and 85 are pivotally attached as at 88 and 89 to a spring abutment collar 90 which is similarly slidable.

15 These control arms with their cooperating trolley wheels serve as releasable connecting members between the outer cylinder 51 and the inner cylinder 59. In the contracted position the trolley wheels 70 and 71 ride on a cam plate 72, thus holding the trolley wheels 66 and 67 up in the annulus 65. The control arms 68 and 69 attached to the spring abutment collar 86 hold spring 37 under compression, the other end of the spring being held in the spring abutment collar 90 which has pivotally secured to it as at 88 and 89 the control arms 84 and 85. These control arms are similar in construction to the control arms 66 and 67 and have at their opposite ends trolley wheels 91 and 92 respectively and have intermediary thereof trolley wheels 93 and 94 respectively which are adapted in the substantially expanded position of the device to seat in the annulus 73 and which in the closed position ride against the inner surface of the cylinder 51. In the contracted position the trolley wheels 91 and 92 ride on the inner cylinder 59 and in the expanded position the trolley wheels 91 and 92 ride up onto the cam plate 74.

20 On both of the cam plates 72 and 73 may be located at a position just beyond the contracted and expanded positions respectively of the trolleys 66, 67, 84 and 85 abutment plates 77 and 78 respectively.

25 A device of this type, as shown in Fig. 5 in its contracted position, may have one end affixed to a stationary point by means of the attaching eye 63 and the other end attached to a movable point as by means of the attaching eye 60. In the closed position the trolleys 66 and 67 being held up into the annulus 65 serve to lock the inner frame 59 and the outer frame 51 together, the ends being pulled together by the action of a spring 27 which is under compression.

30 The spring is kept under compression in the substantially contracted position of the cylinders 75

5 by the spring abutment collar 90 which is held in position by the trolley wheels 91 and 92 of the control arms 84 and 85 abutting against the shoulder 79 of a cam plate 74. Thus separation of the outer cylinder with respect to the inner cylinder will be resisted by the spring.

10 In Fig. 6 I have shown the device in its extended position. In this position the control arms 68 and 69 have slid down so that the wheels 10 66 and 67 are disengaged from the annulus 65 with the result that the wheels 70 and 71 in this position abut against the shoulder 80 of the cam plate 72 so that the force of the spring 87 no longer acts against the cylinder 51 to bring the 15 ends together but is transmitted through the abutment plate 90 pushing against the control arms 84 and 85 and the trolley wheels 93 and 94 now locked in the annulus 73 to force the two 20 ends apart. In this position the trolley wheels 91 and 92 ride on the cam plate 74.

25 It can thus be seen that the device as shown in Figs. 5 and 6 acts not only to hold the parts together but when its effort in this direction has been overcome transmits it in the opposite direction to aid in holding the parts in separated position.

30 While I have described the device as being in contracted relation initially it is readily seen that it may be assembled in expanded position. In such a case it would hold the parts against closing and its operation would be reversed.

35 In Fig. 7 I have shown a form of the invention as described in Figs. 1, 2 and 3 installed in an airplane wing having flaps which aid in decreasing the speed of the plane in landing. In this figure, 101 represents the wing of the plane generally, 102 represents the wing flap or tab which is adapted to be depressed out of the air stream of the wing 101 to act as a brake to reduce the 40 normal speed at which a plane lands and decrease its angle of glide.

45 Flaps of this type are generally provided with means for opening them, such means being either a vacuum or pressure operated cylinder. This cylinder, while satisfactory to open the flaps, does not provide any energy to bring the flaps back and they must be brought back by some independent force. Since the force required to hold the flaps in fully open position is considerable, 50 it is desirable to have as weak a spring as possible to return the flaps to their closed position. Such a spring will serve adequately to hold the flap in closed position when the plane is not flying but because of the construction of the wing section a 55 vacuum is created not only on the top of the wing but at the lower trailing edge of the wing and flap. As a result of this vacuum there is a strong tendency to open the flaps slightly thus spoiling the air foil of the wing.

60 When the flap has been brought to its closed position as shown in Fig. 7 it can be seen that the spring device as mounted with one end attached to a fixed point 103 in the wing and the other end attached to the spring horn 104 as at 65 105 will keep the flaps in closed position.

Assuming that a force of two hundred pounds is required to hold the flap in fully open position against the wind current passing under the wing, it can be seen that with the device of the present 70 invention a main spring having a closing effort of approximately one hundred pounds and a small spring having a closing effort of about ten pounds may be used without necessitating increasing the strength of the opening cylinder but 75 approximately twenty pounds. This is possible as

the flap is opened through the first few degrees there is a vacuum created by the air passing under the wing which tends to open the flap.

The flap, which is here shown as the balanced 5 split type, is pushed down by means of a vacuum cylinder 106 connected as at 112 by the tube 111 to a source of energy not here shown. This cylinder acts through a piston, not shown, and a piston rod 113 connected to a cylinder horn 108 as at 109 which is in turn connected to the flap torque tube 110. Movement of the flap beyond the first few degrees is resisted by the air passing beneath the wing of the plane, and the 10 spring connector 1. As the flap is depressed the spring 37, not here shown, within the cylinder 1 is tripped and no longer exerts a closing action, thus the force of the smaller spring 25, not here shown, in the cylinder 1, is the only force in 15 addition to the air current necessary to be overcome to open the flap. 20

Since the cylinder 106 must have sufficient 25 energization to overcome the air stream, it can be seen there must be sufficient force available to overcome the spring assembly mechanism and the only strength required in addition is about twenty pounds to overcome the small spring at the extended positions.

If it is desired to hold the flaps open, the form 30 of device shown in Figs. 5 and 6 may be used and a two-way cylinder used. Thus one is assured that even should a leak develop in the pressure or vacuum line, the flap will remain in open position as long as desired.

While I have shown the invention as installed 35 in an airplane wing, it is, of course, to be understood that it is not limited to this application but is intended to cover all forms of the device as used in any installation.

Thus I have provided a joinder member which is adapted to be operatively associated with two 40 other members in such a manner that it resists movement of said members in at least one direction.

Furthermore, it is so designed that it may provide an initial resistance to movement of members 45 in one direction and when the members are moved against its resistance will then reverse its action and resist the return of said members to their original position.

Also it may be so constructed that intermediate 50 the positions where it offers resistance or assistance to movement it remains substantially inactive.

The mechanism is simple in construction, cheap 55 to manufacture and has few parts which are subject to wear and consequent deterioration.

While certain novel features of the invention have been disclosed and are pointed out in the annexed claims, it will be understood that various 60 omissions, substitutions and changes may be made by those skilled in the art without departing from the spirit of the invention.

What is claimed is:

1. In a spring assembly mechanism, the combination of an outer tubular member, an inner tubular member adapted to be moved from closed to open position, means, comprising two springs, adapted to resiliently hold said inner and outer tubular members in completely telescoped relation, one of said springs adapted in all positions of said tubular members to urge them into completely telescoped position, the other spring being relatively stronger than said first spring and means for rendering said second spring inactive. 65 70 75

except when said tubular members are in their substantially closed position.

2. In a spring cocking mechanism, the combination of an inner and outer frame member 5 slidable respectively from closed to open position, spring means adapted in the substantially closed position of said members to urge them into closer proximity within limits and in open position adapted to hold said inner and outer frame members in extended position within limits.

3. In a spring cocking mechanism, the combination of two cylinders slidable relatively, spring means comprising a strong and a weak spring adapted to hold said cylinders in telescoped relation, means rendering the stronger of said springs inactive when said cylinders have been pulled apart so that they are not in substantially complete overlap.

4. A reversible spring acting member comprising an outer tube, an inner tube telescoping within said outer tube, an abutment member at the inner end of said inner tube, a pair of slidable collars surrounding said inner tube, a compression spring between said tubes and between said 25 collars, a plurality of control arms pivotally connected to one of said collars, rollers on the ends of said control arms, a cam surface on said inner tube cooperating with said rollers, additional intermediate rollers on said control arms, a recess in said outer tube adapted to receive said intermediate rollers when said outer rollers ride up on said cam surface, a set of second control arms pivotally connected to the other collar, rollers at the other end of said control arms, a cam 30 surface on said inner tube cooperating with said rollers, intermediate rollers on said control arms, a recess on said outer tube cooperating with said intermediate rollers and an abutment secured to said inner tube limiting its movement and an 35 abutment secured to said inner tube and located between said second control arms and the end of said outer tube and a tensor spring within said inner tube connected at one end to the end thereof and at its other end to said outer tube.

5. A device for operably connecting two members comprising a first member and a second member relatively movable, connecting means adapted at all positions of said members within predetermined limits to urge said members relative to each other in a predetermined direction, a second means operative in predetermined positions of said first and second members to effect movement of said members in a predetermined direction relative to each other, a third means operatively connected to said second means and controlled by movement of said first and second members relative to each other to disengage said second means to render it inactive to affect relative movement of said first and second members during movement of said first and second members within predetermined limits.

6. A device for operably connecting two members comprising a first member and a second member relatively movable, means adapted to connect said members in predetermined positions to affect movement of said members relative to each other, a second means operative in predetermined positions of said members to disconnect said first means and render it inactive to affect 65 movement of said members relative to each other, a third means adapted to connect said members in predetermined positions to affect movement of said members relative to each other, a fourth means adapted to disconnect said third means to render it inactive to affect movement of said first

and second members during movement thereof within predetermined limits, all of said means operatively controlled by movement of said first and second members.

7. A wing flap return device comprising an outer tube having an abutment at one end, a tubular extension of reduced diameter connected to the other end of said outer tube, an inner tube telescopically mounted within said outer tube, said inner tube carrying an annular collar member adjacent the inner end of said inner tube, a second annular collar member located in a space between said inner and outer tubes and slidably mounted with respect thereto, a compression spring between said collar members, a cam surface carried by said inner tube, a plurality of control arms pivoted to said annular collar members, each arm carrying at its end a roller engagable with said cam surface and also carrying an intermediate roller, said outer tube carrying an abutment engageable with said intermediate roller and a tensor spring connected at one end to said inner tube and at its other end to said tubular extension located within said inner tube and said tubular extension.

8. A force transmitting device comprising a first member, a second member associated with said first member and movable relative thereto, means energized by relative movement of said members through a predetermined distance for storing energy and means actuated by further relative movement of said members in the same direction for releasing said stored energy to effect further movement of said members in said direction.

9. A force transmitting device comprising first and second members, means associated with said members for providing a predetermined resistance to a relative movement of said members in one direction and active to resist such movement throughout a predetermined distance, a second means active upon further movement of said members for locking out said resisting means and means active upon still further movement of said members in said direction for activating said first means to aid in movement of said members in one direction.

10. A force transmitting device comprising first and second members, means associated with said members for providing a predetermined resistance to a relative movement of said members in one direction and active to resist such movement throughout a predetermined distance, a second means active upon further movement of said members for locking out said resisting means and means active upon still further movement of said members in said direction for activating said first means to aid in movement of said members in one direction, all of said means being reversible upon movement of said members in the opposite direction.

11. A force transmitting device comprising a first member, a second member associated in overlapping relation with said first member and movable relative thereto, means for operatively connecting said members including spring means and a cooperating cam and wheel assembly, said connecting means adapted to be energized by a relative movement of said members through a predetermined distance for storing energy, and means including a second cooperating cam and wheel assembly actuated by further relative movement of said members in the same direction for releasing said stored energy to affect further movement of said members in said direction.

12. A force transmitting device comprising first and second members, means associated with said members for providing a predetermined effect to a relative movement of said members in one direction and active to affect such movement throughout a predetermined distance, means active upon further movement of said members for locking out said first means and means active upon further movement of said members to render said first means again active to affect movement of said members.

13. A force transmitting device comprising first and second members, means associated with said members for providing a predetermined resistance to a relative movement of said members in one direction and active to resist such movement throughout a predetermined distance, means comprising an abutment on one of said members, a cam on said second member, control arms and wheels active upon further movement of said members for locking out said resisting means. 10

ROBERT LEICESTER HALL.
